EDWARD E. GOHEEN, OF JACKSONVILLE, ILLINOIS, ASSIGNOR OF ONE-HALF TO
FLETCHER J. BLACKBURN, OF JACKSONVILLE, ILLINOIS.

POST-HOLE DIGGER.

1,129,345.

Specification of Letters Patent. Patented Feb. 23, 1915.

Application filed September 26, 1914. Serial No. 863,636.

To all whom it may concern:

Be it known that I, EDWARD E. GOHEEN, a citizen of the United States, residing at Jacksonville, in the county of Morgan and State of Illinois, have invented certain new and useful Improvements in Post-Hole Diggers, of which the following is a specification.

This invention is a post hole digger, and has for its object to provide a simple and inexpensive device of this character which will be useful for the purpose designed and which can be manipulated in a very convenient and efficient manner. It is proposed to so construct the device that it may be conveniently employed for removing dirt from a hole as well as for digging the hole, and in this connection it is proposed to so mount the blade upon the handle that the blade 10 may be quickly and conveniently shifted upon its handle from a digging position to a position for removing dirt from the hole, and vice versa, while the blade is in the hole, thereby avoiding the necessity of removing the digger from the hole and going through more or less complicated adjustments to shift the blade from one position to another. While the blade can be conveniently shifted while in the hole, by manipulation of the handle only, the blade will be held in each of its positions with sufficient 20 rigidity to permit of the convenient and efficient use of the device in digging as well as in removing the diggings from the hole.

With these and other objects in view, the present invention consists in the combination and arrangement of parts as will be herein-after more fully described, shown in the accompanying drawing and particularly 30 pointed out in the appended claims, it being understood that changes in the form, proportion, size and minor details may be made, within the scope of the claims, without departing from the spirit or sacrificing any of 40 the advantages of the invention.

In the drawings—Figure 1 is a perspective view of a post hole digger embodying the features of the present invention, the blade being in position for digging. Fig. 2 is a 50 central longitudinal sectional view of Fig. 1. Fig. 3 is a front elevation of the implement. Fig. 4 is a detail sectional elevation of the implement with the blade in position for lifting dirt from a hole. Fig. 5 is a detail 55 sectional view on the line 5—5 of Fig. 2.

Fig. 6 is an enlarged detail fragmentary perspective view of the rear portion of the blade.

Like characters of reference designate corresponding parts in each of the figures of 60 the drawing.

The present implement includes a blade 1, a handle 2 and a ferrule 3. The blade is of metal and of any preferred size and configuration, the lower edge thereof being relatively sharp and of a configuration to facilitate the use of the device in digging. The handle is preferably of wood and in the form of a substantially cylindrical bar. The ferrule connects the handle and the blade as 65 70 will now be described.

The upper portion of the ferrule 3 is preferably cylindrical and snugly embraces the lower end of the handle 2, to which it is rigidly secured by means of suitable fastenings, such, for instance, as rivets. The lower portion 3' of the ferrule extends longitudinally beyond the adjacent end of the handle, and is contracted in width and is of substantial U-shape in cross-section as shown 75 80 in Fig. 5 of the drawing, the open side of this U-shaped portion of the ferrule being at the back of the implement.

The blade 1 is bifurcated or provided with a longitudinal slot 4 intercepting the rear 85 edge of the blade and at the middle thereof. At the inner end of the slot or bifurcation, there is an integral boss or enlargement 5 on the front of the blade, and on the rear end of this boss is a substantially rectangular 90 knuckle 6 which is integral with the boss 5 and of less width than the latter. A transverse opening 7 extends through the middle portion of this knuckle.

In assembling the handle and the blade, 95 the lower portion 3' of the ferrule is received in the slot or bifurcation 4 of the blade, and the knuckle 6 is received within the lower open end of the ferrule, to which it is pivotally connected by a suitable pivot 100 pin 8, whereby the blade may be disposed longitudinally of the handle, as in Figs. 1, 2 and 3, for digging purposes, or it may be swung into a position at substantially right angles to the handle, as in Fig. 4, for the 105 purposes of lifting dirt out of a hole. The lower front end portion of the ferrule is open or cut away as clearly shown in Figs. 1 and 4 of the drawing to permit pivotal movement of the blade. Also the lower ends 110

of each side of the ferrule are rounded or beveled, as best shown in Fig. 1 so as not to interfere with the shoulders 10 of the boss 5 when swinging the blade from one position 5 to the other.

By reference to Fig. 1 of the drawings, it will be noted that the shoulders 10 of the boss engage the extremity of the handle at opposite sides of the bifurcation therein so 10 as to relieve strain from the pivot 8 in the digging position of the blade.

For the purpose of holding the blade in each of its positions, there is a leaf spring 11 disposed within the U-shaped portion 3' of 15 the ferrule and held therein by suitable fastening 12 disposed substantially midway between the ends of the spring. In the position shown in Fig. 2 of the drawing, the lower end of the spring extends into the slot 20 or bifurcation 4 of the blade with its lower extremity bearing against the inner end of the slot or bifurcation and its front side bearing against one edge of the knuckle 6, whereby the blade will be held in its digging 25 position.

The blade may be turned upon its pivot 8, from the digging position, shown in Fig. 2, to the position shown in Fig. 4, the spring 11 yielding sufficiently to permit of the 30 knuckle 6 turning upon its pivot 8 until the front face of the knuckle engages the upper closed end of the bifurcation in the lower end of the ferrule. In this position, the spring 11 will be in engagement with another face or edge of the knuckle, and the 35 blade will be held in its digging position.

A set screw 13 pierces the front of the ferrule immediately below the lower end of the handle and may be set up more or less 40 tightly against the upper end of the spring 11 for the purpose of varying the tension thereof as may be required when wear has developed between the spring and the knuckle.

Having thus described the invention, what 45 is claimed is:

1. A post hole digger comprising a handle, a blade pivoted to the handle and shiftable from a position longitudinally thereof 50 to a position transversely thereof, and vice versa, and a spring carried by one of the members and engaging the other member to hold the blade in each of its positions, said other member having a part provided with surfaces at substantially right angles to one another for successive engagement with the 55 spring, and said part being free to ride upon the spring under relative movements of the members in shifting the blade from one position to another, and means for varying the tension of the spring.

2. A post hole digger comprising a handle, a blade pivoted to the handle and shiftable from a position longitudinally thereof 60 to a position transversely thereof, and vice 65

versa, and a spring carried by one of the members and engaging the other member to hold the blade in each of its positions, said other member having a part provided with surfaces at substantially right angles to one another for successive engagement with the 70 spring, and said part being free to ride upon the spring under relative movements of the members in shifting the blade from one position to another, and a set screw for varying the tension of the spring. 75

3. A post hole digger comprising a handle, a blade pivoted to the handle and shiftable from a position longitudinally thereof to a position transversely thereof, and vice 80 versa, a leaf spring secured intermediate of its ends upon the handle and having its ends free, the blade having a part provided with surfaces at substantially right angles to one another for successive engagement 85 with one end of the spring, said part being free to ride upon the spring in shifting the blade from one position to another, and a setscrew in co-operative relation with the other end of the spring for varying the tension 90 thereof.

4. A post hole digger comprising a bifurcated handle, a blade having a bifurcation receiving the bifurcated handle, said blade also having a knuckle pivoted within the 95 bifurcated portion of the handle and provided with surfaces at substantially right angles to one another, and a spring carried by the handle and disposed for successive engagements with the surfaces of the knuckle 100 which are at substantially right angles to one another to hold the blade in its different positions.

5. A post hole digger comprising a bifurcated handle, a blade having a bifurcation receiving the bifurcated portion of the handle, said blade having a boss at the inner end of the bifurcation, said boss having a knuckle aligned with and extending in front of the bifurcation in the blade and provided with surfaces at substantially right angles to one another, said knuckle being received within the bifurcated portion of the handle and pivoted thereto, and a spring carried within the bifurcated portion of the handle and having a part disposed for successive engagements with the surfaces of the knuckle which are at substantially right angles to one another to hold the blade in its different positions. 110 115

6. A post hole digger comprising a handle, a blade pivoted to the handle and shiftable from a position longitudinally thereof to a position transversely thereof, and vice versa, and a spring carried by one of the members and engaging the other member to hold the blade in each of its positions, said other member having a part provided with surfaces at substantially right angles to one another for successive engagement with the 125 130

spring, and said part being free to ride upon the spring under relative movements of the members in shifting the blade from one position to another.

5 7. A post hole digger comprising a bifurcated handle, a blade having a shank pivoted in the bifurcation and provided with surfaces disposed at substantially right angles to one another, and a leaf spring secured within the bifurcation and having its free extremity disposed for successive engagement by said surfaces of the shank, and said shank being free to ride upon the spring under relative movements of the members in shifting the blade from one of its positions to another.

8. A post hole digger comprising a bifurcated handle, a blade having a shank pivoted in the bifurcation and provided with surfaces disposed at substantially right angles to one another, and a leaf spring secured within the bifurcation and having its free extremity disposed for successive engagement by said surfaces of the shank, and said shank being free to ride upon the spring under relative movements of the members in shifting the blade from one of its positions to another, a portion of the blade lying in substantial engagement with

the adjacent end of the handle in the longitudinal disposition of the blade, and the end of the handle being beveled at its front side to accommodate the blade in swinging about its pivotal connection with the handle.

9. A post hole digger comprising a bifurcated handle, a blade having a bifurcation receiving the bifurcated handle, said blade also having a boss on the front thereof and a reduced knuckle on the boss in alinement with the bifurcation of the blade, said knuckle being pivoted within the bifurcated portion of the handle and provided with surfaces at substantially right angles to one another, the top of the boss at opposite sides of the knuckle constituting shoulders to engage the end of the handle, and a spring carried by the handle and disposed for successive engagements with the surfaces of the knuckle which are at substantially right angles to one another to hold the blade in its different positions.

In testimony whereof I affix my signature in presence of two witnesses.

EDWARD E. GOHEEN.
